UNITED STATES PATENT OFFICE.

EDWARD G. PFAU AND CHARLES PFAU, OF CINCINNATI, OHIO.

FAUCET.

SPECIFICATION forming part of Letters Patent No. 319,845, dated June 9, 1885.

Application filed December 3, 1884. (No model.)

To all whom it may concern:

Be it known that we, EDWARD G. PFAU and CHAS. PFAU, citizens of the United States, residing in the city of Cincinnati, Hamilton county, and State of Ohio, have jointly invented a new and useful Improvement in Faucets, of which the following is a specification.

Our invention relates to improvements in faucets or cocks designed for use on hydrants, whereby the service pipe or pipes can be automatically drained of the surplus water remaining therein. In cold weather this is a special feature, as it prevents the stoppage of the water-supply, plumbing expenses, the bursting of pipes in consequence of the water freezing therein, and the numerous other annoyances too well known to be designated herein. These advantages will be understood from the explanation hereinafter given, and by reference 20 to the accompanying drawings, in which—

Figure 1 is a sectional view of an ordinary faucet with the key thereof partly in section, in the latter of which is illustrated our improvement. This view shows the ports closed, so as 25 to prevent any water passing through the faucet. Fig. 2 is a horizontal section of the key and its contained mechanism, taken through the line x x , Fig. 1, the view being enlarged to double the size of the same parts shown in 30 Fig. 1. Fig. 3 is an enlarged view, in section, showing more clearly than in Fig. 1 the interior construction of our faucet and the position of its different parts.

A is the spout of an ordinary faucet, and B 35 the port through which the water enters from the service-pipe.

C is the handle or key by which the water can be turned on or off.

d is an air-duct running horizontally through 40 the key. The diameter of the key from below the duct d is somewhat enlarged, so that it may contain the chamber hereinafter described.

e is a vertical duct communicating with the duct d .

45 f is a pocket or chamber in the key below the duct e . In this chamber is a plug or valve, p . The length of the chamber f is about twice the thickness of the valve p , and the diameter of the latter is a trifle less than that of the 50 chamber f .

Running from near the bottom of the cham-

ber f and through the rubber packing, which is inserted on the lower end of the key, is a small tube, c . This tube forms a communication between the chamber f and the port B. 55 The end of this tube, as is seen, projects a little below the rubber packing P , and is provided with a screw-thread. Upon this is fastened a small nut, n , or disk. By this means it will be seen that the packing is held securely in place and prevented from being disengaged from the key. It will be noticed that the top of this tube c projects slightly into the chamber f . This projecting portion is provided with a small slot, preferably V-shaped. 60 This slot is shown at s , Fig. 2. The object of this slot is to prevent the total closing of the tube c by the plug p , and to admit of a sufficient amount of air passing therein as will exert a pressure upon the water in port B, and 65 drive it out therefrom and thence from the service-pipe.

The operation of our device is as follows: Let it be supposed that the water is shut off in the faucet, as shown in Fig. 1, and it is desired to obtain a supply. The key or handle is turned in the ordinary way and the packing P is raised so as to permit the liquid to flow from the port B, through the faucet, and out in spout A. The water flowing through the 80 faucet will exert an upward pressure and a portion of it will rise and force itself into tube c , thence into the chamber f , carrying with it the plug or valve p until the latter is forced against the top of chamber f , when it closes 85 the duct e and prevents the water entering therein. After a sufficient supply of water has been obtained the handle C is turned again, so as to shut off the supply of water. The water having been shut off from the service-pipe by 90 means of the ordinary stop and waste cock in the cellar, no upward pressure by the water is exerted, and the valve p is permitted to drop to the bottom of chamber f . By the dropping of said valve air is permitted to flow from the 95 spout A into the horizontal duct d , as shown by the arrows. Continuing its course, it flows from duct d into passage e , and from thence to chamber f . The valve p being smaller in diameter than the chamber f , the air is enabled 100 to circulate around it and into the V-shaped slot s on the upper side of the tube c , as shown.

The air continuing to flow into port B, through the channel *c*, exerts a pressure upon the water in the service-pipe and the liquid flows therefrom, finding an exit in the waste-water tube 5 or aperture which is contained in all ordinary stop and waste-water cocks.

My improvements can be applied to any faucet now in use, whether self-closing or otherwise, and by their adoption it will readily be seen that the pipes can automatically be kept free from water when not desired, freezing and bursting are prevented, and much expense and annoyance saved.

If at any time it be not desired to make use 15 of these improvements, a disk without an aperture can be used instead of the nut *n*. This will close up the tube *e* and prevent the acting of the vent; or the spigot in the cellar or lowest faucet on the premises can be kept 20 closed. This will prevent the escape of the water and consequent non-action of the vent.

We are aware that it is not new to provide the valve of a bib cock with a puppet-valve adapted to fall by gravity and to rise by the 25 pressure of the water to open and close the air-vents, and this idea we do not claim, broadly; but,

Having thus fully set forth our invention, what we do claim is—

30 1. The combination, with the partitioned body of a faucet and a valve-plug for closing the same provided with a cylindrical chamber communicating with the two chambers of the faucet, of a piston loosely mounted within said 35 cylindrical chamber, as set forth.

2. The combination, with the partitioned body of a faucet and a valve-plug for closing the

same provided with a cylindrical chamber communicating at its upper end with the outlet-port of the faucet by lateral passages and at its 40 lower end with the inlet-port by a tube, of a piston loosely mounted in said cylindrical chamber, as shown and described.

3. In a faucet, the combination, with the partitioned body, of a valve-plug therefor provided with a chamber at its lower end communicating with the upper and lower ducts of the faucet and a valve or piston of less diameter than the chamber and placed loosely therein, as and for the purpose set forth.

4. In a faucet, the combination of a partitioned body, a valve or gate for controlling the discharge of water therefrom, said valve or gate carrying at its lower end a chamber, *f*, communicating with the discharge-port by 55 openings *d e*, and with the supply-port by a tube, *c*, and a valve, *p*, of less diameter than and seated in the chamber, and adapted to prevent the egress of water and allow the ingress of air to the chamber, as and for the purpose set forth.

5. The herein-described faucet, consisting of the partitioned body and a valve or plug for closing the same, chamber *f*, provided with openings *d e*, tube *c*, having slot *s*, packing *P*, 65 and nut *n*, and the valve *p*, of less diameter than the chamber *f*, and carried thereby, as and for the purpose set forth.

EDWARD G. PFAU.
CHARLES PFAU.
